UNITED STATES PATENT OFFICE.

LOUIS CHRISTIN, OF GENEVA, SWITZERLAND.

REINFORCED HOLLOW BOARD.

1,329,292.

Specification of Letters Patent. Patented Jan. 27, 1920.

Application filed May 3, 1918. Serial No. 232,397.

To all whom it may concern:

Be it known that I, LOUIS CHRISTIN, manufacturer, a citizen of Switzerland, residing at Geneva, Canton of Geneva, in the 5 federation of Switzerland, have invented certain new and useful Improvements in Reinforced Hollow Boards, of which the following is a specification.

The present invention relates to a reinforced hollow board or plank or the like, intended for any structures in which it can be utilized, in no matter what position. This board or plank may be constructed either of plaster or of strong hydraulic cement, or else partly of plaster and partly of cement.

The accompanying drawing, given by way of example, shows two forms of the subject-matter of the invention.

Figure 1 is a general view, in perspective, of the first form.

Fig. 2 shows on a larger scale, also in perspective and in section, a portion of the board or plank illustrated in Fig. 1.

Fig. 3 shows sewn tubes or reeds in the position they occupy in the portion of the plank shown in Fig. 2, before the manufacture of the plank.

Fig. 4 is a plan of a mold capable of serving for the manufacture of a plank such as the one shown in Fig. 1.

Fig. 5 is a section through A—B in Fig. 4.

Fig. 6 shows separately the part *l* of the mold shown in Figs. 4 and 5.

Fig. 7 shows the second constructional form, and Fig. 8 is a section through a mold serving for the manufacture of the plank.

Figs. 9 to 12 show modifications in or connected with the reinforced hollow board, 40 plank or the like, shown in the other figures.

The plank shown in Fig. 1 is formed of two reinforced parts *a* and *b*, connected together by a longitudinal rib *c*, the whole comprising a reinforcement of tubes or reeds 45 *d* sewn into a sheet folded back upon itself like the cover of a book, as is seen in Fig. 3. The metal wires *e* forming the stitching of the tubes or reeds, form a supplementary reinforcement which connects together the

50 parts *a* and *b*. The metal wires *e* thus employed to secure the tubes or reeds together are of sufficient strength and rigidity to maintain the tubes or reeds in the position shown in Fig. 3 or in other positions in which

55 they may be placed in the mold so as to main-

tain these reinforcing members in the desired position while the body of the block is poured around the same.

The latter are maintained at the desired distance apart with respect to one another 60 by the longitudinal rib *c* and by transverse ribs *f* integral with the parts *a* and *b*. These ribs *f* are pierced in the direction of their length with holes *f'* which are intended to receive iron bars connecting together 65 a series of similar planks, as the string of a rosary connects together the beads of the latter. The three full faces of the edge of the plank are provided with a groove *g* serving to form the joint with the adjacent plank, either by the insertion of a round iron bar lodged partly in one plank and partly in the adjacent plank, or by pouring plaster or cement into the hole formed by two contiguous grooves.

75 The dimensions of the plank and the number of its ribs may vary.

For the manufacture of the plank illustrated in Figs. 1 to 3, a mold of which one form is partly shown in Figs. 4 to 6, may 80 advantageously be employed.

This mold comprises a plank *h* assumed to be horizontal in the example illustrated. On this plank *h* forming the bottom of the mold is arranged a frame formed of the full 85 sides *i* and *k* and of a perforated side *l*. A second side *i* is not visible in Fig. 4, which is broken. The side *l* of the frame is provided with openings *l'* for the passage of the cores *m* and holes *l''* for the passage of the rods *r* 90 that serve to form the holes *f'* in the ribs *f*. The ribs *f* are formed by the space that separates two cores *m* from one another, and in order that these cores may be able to be withdrawn from the plank easily after the 95 latter has been cast, they are in the form of wedges. For the same purpose each core is provided with a nut *n* traversed by a screw *o* which bears upon an iron key *p* passing through an elongated aperture in 100 the core and bearing on the bar *l*. This device may be replaced by levers engaging in openings in the cores and bearing on the bar *l*.

105 The plank illustrated in Fig. 7 differs from that of Fig. 1 by the fact that it comprises no longitudinal rib *c*.

Fig. 8 shows a mold serving for the manufacture of this constructional form. In this mold the cores *m* pass through the two sides 110

l and *k* of the mold, so that they can be easily extracted by striking lightly on the ends projecting from the side *k* of the mold.

The plank described in reference to Fig. 1, 5 as well as the one described in reference to Fig. 7, may be constructed entirely of plaster, or entirely of cement, which envelops the tubes, reeds or the like, or by making one of the parts *a* or *b* of plaster and the 10 other of cement. In the latter case hooks or cramp irons will be lodged in the mass, so as to connect together the plaster and the cement.

The improvements shown in Figs. 9 to 11, 15 consist in providing such boards or planks with miter tongues *h*¹ intended to enter and engage corresponding recesses in the adjacent boards as indicated in Fig. 11 of the drawing. Fig. 12 shows how a similar miter 20 *h*² may be made of a separate piece with the board as in the Figs. 9 to 11.

These planks may be employed very advantageously for temporary structures.

I claim.

A section of molded rectangular plank 25 comprising spaced parts connected at one side by a longitudinal rib and also connected by transverse ribs running at an angle to the longitudinal rib whereby there is formed an opening in the block bounded 30 by the said ribs and extending from the said longitudinal rib to the opposite side of the plank, and a plurality of spaced reinforcing tubes extending longitudinally of the plank and connected to one another by 35 wires running transversely through the members of the plank so that when in position, the reinforcing member is folded back upon itself like a cover on a book.

In testimony whereof I have affixed my 40 signature in presence of two witnesses.

LOUIS CHRISTIN.
